UNITED STATES PATENT OFFICE.

NELSON I. PERRY, OF CHICAGO, ILLINOIS.

LAUNDRY MACHINE.

Application filed October 23, 1924. Serial No. 745,320.

To all whom it may concern:

Be it known that I, NELSON I. PERRY, a citizen of the United States, residing at Chicago, in the county of Cook and State of Illinois, have invented certain new and useful Improvements in Laundry Machines, of which the following is a specification.

The invention relates to improvements in laundry machines.

10 One of the objects of the invention is to provide a machine which may be used for washing and also for drying the clothes.

Another object is to provide an incomplex, inexpensive construction which is efficient 15 in operation.

Another object is to provide a machine which may be operated by hand or by power.

Another object is to provide a machine having a rotatable clothes holding member 20 and in which machine the water is prevented from partaking of a rotary motion.

Other objects, advantages and benefits will hereinafter appear from a consideration of 25 the following description, when taken into consideration with the drawings, wherein:

Fig. 1 is a central, transverse section of a machine showing the invention.

Fig. 2 is an axial section.

In all the views the same reference characters indicate similar parts.

The casing constituting a tub-part 5 and a cover 6 are substantially cylindrical in cross section when the cover is in place, as shown in Fig. 1, and each is substantially 30 semi-cylindrical. The cover is hinged to one edge of the tub at 7 and latched to the opposite edges at 8.

There are two lateral, longitudinal enlargements 9, one on each side of the tub, each having an abrupt wall 10, forming a shoulder facing downwardly and a gradually inclined wall 12 blending into the circular part of the tub at 13.

40 The end walls 14 of the casing are held by spider formations 15 overlapping the circumferential edges at 16 and affording a bearing 17 for rotatable shafts 18 and 18' and legs 19.

A clothes containing basket 20 is rectangular in form in every direction. It has imperforate side walls 21, the remaining portion of the basket is reticular in form.

One side of the basket 20 is provided with two covers 22, hinged to a cross-bar 23.

They may be opened and closed to place 55 the clothes within the basket and to take them therefrom.

A handle 24 is a means for rotating the basket which may be rotated in either direction.

Legs 25 extend to and over the lateral enlargements and form parts for the hinges 7 and the latch 8. They are connected together by the band 26.

60 Legs 25 extend to and over the lateral enlargements and form parts for the hinges 7 and the latch 8. They are connected together by the band 26.

Legs 25 extend to and over the lateral enlargements and form parts for the hinges 7 and the latch 8. They are connected together by the band 26.

A drain cock 27 is connected with a pipe 28 65 to drain the tub.

The operation of the device is as follows:

The casing is partly filled with water to the water line shown. Soap is put into the 70 water and the handle turned rapidly to rotate the empty basket. This soon makes a good suds. The basket is opened and the clothes to be washed are placed in the basket and the handle again turned a few revolutions in one 75 direction and reversed and rotated as many revolutions in the opposite directions.

When the basket is rotated the water is prevented from rotating therewith by the lateral enlargements. The water will strike 80 the abutments or shoulders 10 and will thereby be caused to take a backward course as shown by the arrows.

By this means the water will be forced 85 thru the clothes in the reticular basket. The clothes will also shift from the center towards the respective ends as the basket is rotated producing a washboard action upon the clothes as they are rubbed against the irregular surfaces of the basket.

90 After the clothes have thus been washed, the drain cock 27 is to be opened and the water drained off. The cock is to be left open and the basket is to be again rotated at a high speed. The clothes will, therefore, be 95 squeezed by centrifugal action at the ends of the basket and the water thus expressed from them. The water will drain out thru the drain cock and the clothes will be substantially dried without removing them from 100 the basket.

In order that the basket may be evenly balanced substantially the same quantity of clothes should be placed in each side of the basket.

105 The device may also be used for expressing juice from grapes and for many other useful purposes.

Having described my invention what I claim as new and desire to secure by Letters Patent, is:—

1. In a washing and drying machine, a substantially cylindrical casing having two lateral horizontal enlargements in a plane below its axis terminating in shoulders facing downwardly in direction and a gradually inclined connecting surface, and a rotatable, reticular and rectangular clothes-holding basket journaled at the axis of said casing and means to rotate the basket.
2. In a washing and drying machine, a casing substantially cylindrical in form, hav-

ing two lateral enlargements extending longitudinally thereof in a horizontal plane and located below the axis of the casing, one wall of said enlargement forming a downwardly facing shoulder and the connecting wall being inclined and blending into the circular part of the casing in combination with a rotatable, reticular rectangular clothes-holding basket having substantially imperforate side walls and journaled at the axis of said cylinder and means to rotate the basket.

In testimony whereof I hereunto set my hand.

NELSON I. PERRY.
